GRINDING MACHINE

Herman R. Isler, Norwood, Ohio, assignor to The Cincinnati Milling Machine Company, Cincinnati, Ohio, a corporation of Ohio

Application December 31, 1931
Serial No. 584,189

21 Claims. (Cl. 51—92)

This invention relates to grinding machines and more particularly to an improved cutter grinder that may be utilized not only for sharpening cutters but for general purposes such as 5 cylindrical and plane surface grinding operations.

An object of this invention is to provide a grinder for the purposes stated, having a simple and compact transmission for effecting power movement of the table in a plurality of selective 10 automatic cycles.

Another object of this invention is to provide an improved mechanism for effecting relatively large increments of feed with respect to a surface grinding wheel without increasing the length of 15 the normal or necessary grinding stroke of the work.

A further object of this invention is to provide an improved hydraulically actuated cross feed mechanism for a surface grinding machine.

An additional object of this invention is to provide a simplified and improved hydraulic variable feed transmission for a reciprocating grinding machine table having a cycle selector whereby the table may be automatically reversed at 25 each end of its stroke; or at either end with a subsequent stop at the end of the succeeding stroke; or an automatic stop at the end of each stroke.

Other objects and advantages of the present 30 invention should be readily apparent by reference to the following specification considered in conjunction with the accompanying drawings illustrative of one embodiment thereof, but it will be understood that any modifications may be made 35 in the specific structural details within the scope of the appended claims without departing from or exceeding the spirit of the invention.

Referring to the drawings in which like reference numerals indicate like or similar parts:

40 Figure 1 is an elevation of a grinding machine embodying the principles of this invention.

Figure 2 is a plan view of the machine shown in Figure 1.

Figure 3 is a section through the feed transmission box as viewed on the line 3—3 of Figure 2.

Figure 4 is a detail sectional view through the reverser valve shown in Figure 3.

50 Figure 5 is an expanded view of the cycle selector drum.

Figure 6 is an expanded view of the feed transmission for the table.

Figure 7 is a detail view of the detent mechanism for the reversing lever.

Figure 8 is a sectional view on the line 8—8 of Figure 3.

Figure 9 is a sectional view through the feed box showing the relief and throttle valves partly in section as viewed on the line 9—9 of Figure 8. 60

Figure 10 is a plan view partly in section showing the cross feed mechanism.

Figure 11 is a section on the line 11—11 of Figure 10.

Figure 12 is a section on the line 12—12 of Figure 11.

Figure 13 is a section on the line 13—13 of Figure 11.

Figure 14 is a detail section on the line 14—14 of Figure 13. 70

Figure 15 is a detail section on the line 15—15 of Figure 3.

Figure 16 is a detail view showing the indicia on the throttle valve indicator dial.

Referring to Figure 1 of the drawings, the 75 reference numeral 10 indicates the base of the machine having guideways 11 formed upon the top thereof for receiving a reciprocating saddle 12. A wheel head 13 is adjustably mounted on the bed of the machine for vertical adjustment 80 or rotatable adjustment relative to the saddle but the mechanisms for effecting these adjustments are not shown as they do not constitute any part of this invention. A prime mover, not shown, is mounted in the bed for effecting rotation of the grinding wheel. 85

A work table 14 is reciprocably mounted on the saddle for transverse movement relative to the grinding wheel 15 journaled in the head 13.

A self-contained hydraulic transmission is 90 mounted in a transmission housing or casing 16 depending from the under side of the saddle, as more particularly shown in Figure 3, for effecting reciprocation of the work table. Fluid pressure is generated by an hydraulic pump 17 95 which is driven from a prime mover, such as an electric motor 18, mounted in an exterior pocket 19 formed in the wall of the transmission casing. The armature shaft 20 of this motor projects into the housing where it is provided with a spiral gear 21 meshing with the spiral gear 22 secured to the end of the pump drive shaft 23. Actuation of the electric motor will therefore effect continuous rotation of the pump. This pump may be of any suitable construction, 105 the one illustrated being a constant delivery gear type pump. The lower part of the transmission casing constitutes a fluid reservoir 134 from which oil is drawn through the pump intake 24 and forced under pressure through the 110

conduit 24 to a relief valve 25 shown more particularly in Figure 9. The reservoir is filled by removing plug 135, and a gauge glass 136 serves to indicate the oil level, a drain plug 137 is provided in the bottom of the reservoir.

The relief valve is provided with a reciprocating plunger 26 which is normally held in position by means of spring 28 to close overflow outlet 27. This valve permits escape of fluid 10 from the system when the pressure therein has reached a predetermined maximum as determined by the setting of the spring 28. This setting may be varied by the adjusting screw 28'. A port 29 formed in the side of the valve 15 communicates with a throttle valve 30 in which is reciprocably mounted a tapered valve plunger 31. This plunger is provided with a tapered portion 32 which determines the amount of flow through the port and thereby the rate of 20 movement of the table, and a reduced annular portion 32' around which the fluid pressure will flow when the valve is in an open position as shown in Figure 9 thereby conducting the fluid to channel 33. The valve plunger 31 is formed 25 on one end with a plurality of rack teeth 34 engageable by rack pinion 35 formed on the end of a rotatable shaft 36. This shaft projects through a bushing 36' in the forward wall of the casing and has keyed thereto a knurled adjusting knob 37 and has threaded on the end thereof a locking nut 37'. As shown in Figure 16, the projecting end of the bushing has a reference mark scribed thereon while the knob 37 is provided with indicia marks cooperating 30 with the reference mark to show the rate at which the table will move for each setting. It is apparent that rotation of the knob will effect longitudinal movement of the valve and thus vary the opening of port 29 and the flow 35 of fluid to the motor. Tightening of the locking nut 37' serves to hold the valve in its adjusted position.

The channel 33 conducts the fluid to a reversing valve 38 as shown in Figure 8 which determines its direction of flow to the hydraulic motor 39. As shown in Figure 4, a valve piston 40 is reciprocably mounted in the reversing valve housing and is provided with an annular groove 41 whereby upon movement of the valve 45 to the right as viewed in this figure, the fluid will be conducted to channel 42 leading to one side of the motor 39; or upon movement to the left, fluid will be conducted to the channel 43 leading to the other side of the hydraulic motor. The piston 40 is also provided with shoulders 44 and 45 upon opposite ends whereby upon movement of the valve plunger to the right to conduct fluid pressure to channel 42, the fluid 50 in channel 43 will be allowed to escape to the exhaust port 46 and similarly, upon movement to the left, the fluid in channel 42 will escape to the exhaust port 47. Thus shifting of the valve from one extreme position to the other will change the direction of motor rotation, while 55 movement to a central or neutral position will cut off all flow to the motor and the table will stop.

The motor 39 may be of any suitable construction in which a constant flow of fluid pressure therethrough will effect rotation of the motor shaft. In the present instance this motor is of the gear type and the method of operation is that the fluid pressure from channel 33 will flow through the reversing valve in channel 70 43 to effect rotation of the motor shaft in one

direction, the exhaust fluid returning through channel 42 and port 47 to the reservoir. Shifting of the reversing valve will cause a reverse direction of flow through the motor rotating the motor shaft in the opposite direction, the exhaust fluid returning through channel 43 to reservoir. The speed of rotation of the motor may be varied by adjusting the throttle valve 31 by means of the control knob 37 located on the front of the machine.

The motor shaft 48 as shown in Figure 3 is provided with a spiral gear 49 which meshes with a spiral gear 50 mounted for free rotation on the horizontal shaft 51 upon assembly of detachable housing 16 with the saddle. The gear 50 is fixed to the sleeve 52 which has clutch teeth 53 formed on the end face thereof. Fixed to the shaft 51 is a selector clutch member 54 having clutch teeth 55 formed on the end thereof for engaging the clutch teeth 53 and thereby coupling the gear 50 to the shaft 51. This coupling is effected by longitudinally sliding the shaft 51 by means of the control knob 56. Keyed to the end of the shaft 51 is a pinion 57 which meshes with a rack 58 fixed to the under side of the table 14. From the foregoing it will be seen that a variable speed hydraulic transmission has been provided for the table, comprising a pump and a motor, and means to vary the flow of the pump fluid to the motor together with a relief valve permitting the discharge to reservoir of excess fluid and a selector clutch by which the motor may be selectively coupled to the table for actuation thereby.

The shift clutch member 54 has integrally formed therewith a gear 59 which meshes with a pinion 60 forming part of a gear couplet, the other member 61 of which meshes with a gear 62 fixed to the end of a shaft 63. This shaft extends through the front wall of the housing and has fixed to its outer end the hand wheel 64. Upon movement of the clutch to the position shown in Figure 6, it will be seen that the gear 59 is in mesh with the gear 60 whereby rotation of the hand wheel 64 will effect longitudinal movement of the table through the gear train just described. The member 54 may also be moved to a neutral position in which the gear 59 will be out of mesh with the gear 60 and the clutch teeth 55 out of mesh with the clutch teeth 53. In this position of the clutch, 110 the table 14 may be manually pushed or pulled back and forth as when the machine is utilized for cutter grinding purposes. In order to maintain the shaft 51 in any one of its three positions, three annular grooves 65 are formed on the shaft 115 and a spring pressed pawl or detent 66 is mounted in the shaft bushing for engaging any one of these grooves to thereby maintain the shaft in any one of its shifted positions.

The reverse valve plunger is shifted back and forth by means of the following mechanism. A shifter rod 67 is rotatably and reciprocably mounted in the upper part of the saddle and provided with a cycle selector drum 68 which is pinned to the shaft for axial and rotative movement there- 120 with. As shown in the expanded view in Figure 5 the selector drum is provided with a peripheral groove 69 for receiving the shifter pin 70 secured to the end of the valve plunger 40. A second annular groove 71 is formed in the periphery of the 125 selector drum for receiving the depending pin 72 of the reversing lever 73. As shown in the development of the drum in Figure 5, the circumference thereof is divided into four equal sectors by longitudinal or detent grooves 74, 75, 76 and 77. 130

Each of these grooves are 90° apart which makes it possible to rotate the shifter rod 67 to any one of four different positions, and a spring pressed 5 detent 78 as shown in Figure 15 will maintain the rod in that position. If the shifter rod 67 is rotated to such a position that the groove 75 is coplanar with the pin 70, extending into the groove 69, it will be apparent that oscillation of the control lever 73 will immediately effect lateral movement 10 of the pin 72 and longitudinal shifting of the reversing valve. If the shifter rod 67 is now rotated through a 90° arc in either a clockwise or a counter-clockwise direction, either the groove 76 or the groove 74 will then be coplanar with the 15 pin 70. In either one of these positions, it will be seen that a recess such as 79 or 79' formed in the sides of the groove will be opposite to the pin. These recesses permit a certain amount of lost motion 20 between the pin 70 and the side of the slot, which must be taken up before movement of the valve begins. This permits shifting by the usual load and fire mechanism shown in Figure 7. Movement of the pin 72 away from groove 79 or 25 79' will cause its engagement with the straight wall of the slot, as in the first instance, which will thereby move the valve to a neutral position.

A further rotation of the rod 67 through an angle of 90° in the same direction as the first movement will bring the pin 70 coplanar with the 30 groove 77 and in that position it will be noted that there is a recess formed in the groove 69 on each side of the pin 70. This permits lost motion 35 on each side of the pin 70 whereby the valve may be shifted by load and fire mechanism in either direction thereby making it possible to effect a reciprocating cycle. The reversing control lever 73 is pivotally mounted in the upper wall of the housing on one end of a pin 80 which has fastened 40 to the lower end, by means of a tapered pin 81, a detent member 82. A spring pressed detent 83 is mounted in cooperative engagement with the detent for maintaining the same in either one of 45 two positions and by means of its cam shaped end will serve to fire the lever from one position to the other upon an angular movement sufficient to move the pointed end of the detent 83 past the peak 84 formed on the detent.

A reciprocable member 85 is mounted in the hollow of the reversing lever 73 and is maintained 50 in a projecting position beyond the end thereof by a spring 86 interposed between a shoulder 87 formed on the member and a plug 88 fixed in the end of the lever 73. This projecting end 89 is adapted to be engaged by suitably positioned dogs 55 90 mounted in slots 91 formed in the front side of the table. By means of this mechanism the reversing valve may be manually or automatically controlled; and, by suitably positioning the cycle selector drum, any one of four cycles of movement 60 may be obtained. These cycles comprise a constantly reciprocating cycle corresponding to detent 77 in which the table is automatically reversed at the end of each stroke; a one-way cycle 65 in which the table is reversed at the end of one stroke and stopped at the end of the succeeding stroke. This one-way cycle may be effected so that the automatic reverse will take place at either the right hand end of the table corresponding to 70 detent 76 or at the left hand end of the table corresponding to detent 74. The selector drum may also be set to stop the table at the end of each stroke, corresponding to detent 75, in which case 75 no automatic reverse will take place; but it will be necessary for the operator to longitudinally

shift the rod 67 in the direction in which he desires the table to move.

As shown in Figure 2 the shifter rod 67 extends to opposite ends, of the table whereby the operator, if standing at either end of the table or 80 upon either side thereof, may reach the control knobs 92 secured to opposite ends of the rod 67 and longitudinally shift the reversing valve to start the table or change its direction of movement. When the machine is utilized for cutter 85 grinding purposes the operator usually stands at the rear of the table and holds the work with his right hand in which case he may not be able to reach the control knob 92. For this reason a shaft 93 is rotatably mounted upon the side of 90 the machine and provided on one end with a bifurcated lever 94 engaging the end of the shifter rod 67 and on the other end with a control lever 95. By this means the operator may move the shifter rod 67 with his left hand while holding 95 the work with his right hand.

The saddle 12 is reciprocably mounted upon the bed 10 as previously explained and this movement may be effected by means of a feed screw 96 journaled at opposite ends in the saddle and 100 engaging a nut 97 fixed in the bed. Hand wheels 98 are keyed to opposite ends of the feed screw for effecting rotation of the screw and thereby movement of the saddle from an operating position at either the front or rear of the machine. 105 As shown in Figure 10 the shaft 96 is also provided with a dial 99 for indicating the amount of movement effected in the saddle.

For imparting increments of feed to the saddle to effect transverse adjustment of the table, 110 the shaft 96 has keyed thereto a spur gear 100 which meshes with a gear 101 secured to the stub shaft 102 as shown in Figure 13. As shown in this figure the gear 101 is provided with an 115 elongated hub 103 in which is formed a pair of segmental grooves 104 and 105. These grooves are axially spaced and are formed on diametrically opposite sides of the hub. In each groove a latch dog or double pawl 106 is pinned to a 120 shaft 107 for pivotal movement, the shaft having a pinion gear 108 secured to the end thereof. The pinion gears 108 and 108' mesh with gear teeth 109 formed on the end of the member 110 which is mounted for free rotation on the shaft 102. A control knob 111 is secured to the periphery of the member 110 and has a flange 112 surrounding the pinion gears 108 and 108'. Each latch dog 106 is provided with a pair of flat angular surfaces 113 alternately engageable by a 125 spring pressed strip 114. This strip is engaged at opposite ends by springs 115 which are positioned beyond the latch dog so that as the dog is turned from one position to the other the pressure will be brought to bear near the center of the strip. Each of these flat surfaces 113 terminates in a pawl 116 which is engageable in notches 117 formed interiorly of the trigger gears 118 and 118'. Upon rotation of the gear 118 in a counter-clockwise direction as viewed in Figure 14, 130 140 it will be seen that the dog 106 will be slightly rotated in a counter-clockwise direction against the pressure of the springs 115 and the pawl will ratchet by the notches; while upon rotation of the gear in a clockwise direction the dog 106 145 would tend to be rotated in a clockwise direction but since the flat surface 113 bearing against strip 114 will prevent this movement, the gear 101 will be rotated with the gear 118.

The gear 118 meshes directly with a rack bar 150

- 119 while the gear 118' is operatively connected to the rack bar 120 thru an intermediate pinion 121 shown in Figure 12. Each of these rack bars are reciprocably mounted in separate cylinders 5 122 and 123 formed in the casting 124 attached to the saddle. The rack bars are in the form of pistons and admission of pressure to one end of the cylinders will effect simultaneous reciprocation of the rack bars in the same direction and 10 rotation of the mechanism coupled therewith. In order to limit the longitudinal movement of the rack bars and thereby predetermine the amount of rotation to be imparted to the trigger gears, adjustable stop members are provided at the 15 opposite end of each cylinder, comprising a member 125 threaded in the end of the cylinder and provided with a stop block 126 on the inner end thereof, and a lock nut 127, whereby after adjustment of the screw by the knurled knob 128, the parts may be locked in position. By this arrangement it will be seen that a short longitudinal movement of the rack bars will effect a short feed increment of the saddle and a long movement of the rack bars will effect a longer feed 20 increment in the saddle.

As it is customary to have any infeeding relative to a grinding wheel take place at the end of a cutting or grinding stroke, means have been provided for effecting reciprocation of the rack bars at the same time that reversal of the table occurs. As shown in Figure 10, it will be recalled that the pressure in line 43 passes through the hydraulic motor 39 and returns by line 42 to effect a feeding movement of the table in one direction, and upon reverse the pressure then flows in the line 42 to the hydraulic motor and returns through line 43. From this it will be seen that lines 42 and 43 are alternately under 30 pressure and that the change effects reverse movement of the table. Each of these lines is therefore extended, conduit 129 forming an extension of line 43, and conduit 130 forming an extension of line 42, the conduit 129 being connected to the port 131 formed in the right end of the rack bar cylinders and the conduit 130 being connected to the port 132 formed in the left end of the rack bar cylinders. It will be noted 35 from Figure 10 that a port 133 permanently connects together the right end of each cylinder so that upon admission of pressure to port 131, both rack bars will be moved simultaneously to the left. Also, it will be noted that the port 132 is formed intermediate the left end of both cylinders 40 whereby pressure entering this port will simultaneously enter both cylinders thereby shifting both rack bars simultaneously to the right. From this construction it will be seen that the shifting of the rack bars is automatically taken 45 care of by simply reversing the direction of movement of the table.

The operation of the saddle feed mechanism is as follows: Upon admittance of pressure to the port 131 both rack bars will move to the left. 65 The rack bar 119 meshes directly with the trigger gear 118 thereby effecting clockwise rotation of the gear 101. Simultaneously, the rack bar 120 will be moving toward the left effecting clockwise rotation of the gear 121 which in turn will rotate the trigger gear 118' in a counter-clockwise direction. The pawl 106' of this gear is set 70 opposite to the pawl 106 so that during this counter-clockwise movement the pawl will ratchet by 75 the teeth of gear 118'.

Upon admission of pressure to the left end of the rack bar cylinders, the rack bar 119 will rotate the gear 118 in a counter-clockwise direction causing the pawl 106 to slip, while the rack bar 120 will rotate the gear 121 in a counter-clockwise direction and thereby gear 118' in a clockwise direction causing its pawl 106' to engage ratchet teeth which will rotate the hub of the gear 103 in a clockwise direction. From this it should be seen that irrespective of the direction of movement of the rack bars that the final resultant motion in the hub 103 is the same or as in the illustration given, in a clockwise direction. Thus at the end of each stroke of the table, the saddle will be given a uni-directional feed movement to vary the relation between the tool and work. After the tool has been moved across the work in step-by-step increments by the method just described as in surface grinding operations, the knob 111 may be rotated to change the position of the pawls 106 and 106' which will thereby cause a uni-directional feed movement in the opposite direction and make it possible for the tool to retraverse the work in an opposite direction to effect a finishing operation. 100

From the description just given it will be seen that a feed movement was imparted to the saddle at the end of each table stroke but if so desired the members 125 may be moved toward one another where they will simultaneously abut the 105 opposite ends of either piston thereby preventing its movement and thus reducing the amount of feed imparted to the saddle by permitting the feeding movement to take place after each reciprocation of the table rather than at the end 110 of each stroke of the table. The direction of this feeding movement may again be determined by the position of the rotatable knob 111 which determines the setting of the pawls 106 and 106'.

From the foregoing it should now be seen that 115 an improved grinding machine has been provided which is especially suitable for surface grinding operations and which is provided with an improved hydraulic transmission which is practically infinitely variable between its upper 120 and lower limits and which is provided with a cross feed mechanism whereby large increments of feed may be quickly obtained without increase in table stroke.

What is claimed is:

1. A grinding machine having a bed, a grinding wheel journaled on the bed, a saddle reciprocably mounted on the bed, a work support mounted on the saddle for reciprocation relative to the grinding wheel, a transmission casing depending from the saddle, means mounted in the casing to effect reciprocation of the work support including a rotatable member, an hydraulic motor for effecting rotation of said member, a pump, means coupling the pump to the motor, a prime 130 mover mounted on the casing for actuating said pump, a throttle valve between the pump and motor, and manual means on the exterior wall of the casing for adjusting said valve to determine the rate of rotation of said motor and thereby 140 the rate of movement of the work support.

2. A grinding machine having a bed, a grinding wheel and a saddle mounted on the bed for relative adjustment with respect to each other, and a work support mounted on the saddle for 145 reciprocating work relative to the grinding wheel, a transmission casing depending from the saddle having a reservoir in the bottom thereof, means to effect reciprocation of the work support including a rotatable member, an hydraulic motor 150

- for effecting rotation of said member, a prime mover, a pump actuated by the prime mover, said pump having an inlet connected to the reservoir and an outlet, means coupling the outlet to the motor including a throttle valve and a relief valve, means to adjust the relief valve to determine the pressure in the system and manually operated means including a rack and pinion for adjusting said throttle valve to determine the rate of movement of the work support. 5
3. A grinding machine having a bed, a grinding wheel journaled on the bed, a saddle reciprocably mounted on the bed for relative movement with respect to the grinding wheel, a work support mounted on the saddle for feeding work past the grinding wheel, a transmission housing depending from the saddle having a reservoir formed in the bottom thereof, means to effect reciprocation of the work support including a rotatable member, an hydraulic motor for effecting rotation of said member, a prime mover, a pump actuated by the prime mover, said pump having an inlet through which fluid is drawn from the reservoir and delivered to the motor, means coupling the pump to the motor including a relief valve, a throttle valve and a reverse valve in the order recited, means to adjust the relief valve to determine the pressure in the system, a manual control on the front wall of the casing for adjusting the throttle to determine the rate of movement of the work support, a reverse control lever mounted on the top of the saddle adjacent the end of the table for shifting said reverse valve either manually or automatically. 10
4. A machine tool having a bed, a grinding wheel journaled on the bed, a saddle mounted on the bed for adjustment relative to the wheel, a work support reciprocably mounted on the saddle, a shaft journaled in the saddle, means coupling one end of the shaft to the table, a driven gear rotatably mounted on the shaft and a transmission housing depending from the saddle having a self-contained hydraulically actuated transmission mounted therein, said transmission terminating in a driving gear adapted to mesh with the driven gear upon assembly of the housing to the saddle to thereby couple the transmission to the table for actuation thereby. 15
5. A machine tool having a bed, a grinding wheel journaled thereon, a saddle adjustably mounted on the bed for movement relative to the grinding wheel, means to effect said saddle adjustment, a table reciprocably mounted on the saddle, a transmission housing depending from the saddle having a reservoir in the bottom thereof, an hydraulically actuated transmission in the housing including a pump, a prime mover for actuating said pump, an hydraulic motor driven by the pump, means coupling the motor to the table for actuation thereby, a removable plug in the saddle for filling said reservoir, a gauge glass mounted in the front wall of said housing for determining the amount of oil in the reservoir and a drain plug in the bottom of said casing for withdrawing the oil therefrom. 20
6. In a machine tool having a translatable member, a power transmission for effecting movement of the member including an hydraulically actuated motor, hydraulic means for actuating said motor, including a pump, a prime mover for actuating said pump, a throttle valve coupling the pump to the prime mover, means to shift said throttle valve to change the rate of rotation of the motor including a shaft, a rack and pinion connection between the shaft and valve plunger, a control knob keyed to the shaft, a fixed dial associated with the knob having rate indicating indicia thereon, a lock nut for securing the shaft and valve in adjusted position, a mechanical transmission extending from the hydraulic motor to the translatable member and a selector clutch for coupling the motor to said transmission for actuation at the selected rate. 25
7. In a machine tool having a translatable support, a power transmission for effecting movement of said support in various cycles including an hydraulic motor, means coupling the motor to said support, a prime mover, a pump actuated by the prime mover for supplying pressure to the motor, a reverse valve interposed between the pump and motor, said reverse valve having a neutral position and a power transmitting position on each side thereof and selector means effective on the reverse valve to obtain a continuous reciprocating cycle of movement in the support, a single reciprocation with a stop at the left end, a single reciprocation with a stop at the right end, or a movement in a given direction and stop. 30
8. A grinding machine having a bed, a grinding wheel journaled on the bed, a work table mounted on the bed for reciprocation relative to the wheel, power means for effecting said reciprocation including an hydraulic motor, a pump, a prime mover for effecting rotation of the pump to supply pressure to the motor, valve means interposed between the pump and motor for determining the rate and direction of movement of the work support, transmission gearing coupling the motor to the table including a rotatable shaft, rack and pinion means coupling the shaft to the table, a pair of spiral gears one of which is mounted for free rotation on the shaft and the other secured to the motor shaft, a clutch member fixed to the shaft and engageable with the spiral gears thereon to effect reciprocation of the table by the motor, a gear train, manual means for actuating said train, means to shift said clutch into operative engagement with the train for manual reciprocation of the table, detent means for maintaining the shaft in either power transmitting position and additional detent means for maintaining said clutch in a neutral position whereby the table may be manually shifted by direct pressure without interference from the gear train or the hydraulic motor. 35
9. In a machine tool having a saddle and a translatable support mounted thereon, a power transmission for effecting movement of said support in various cycles including an hydraulic motor, means coupling the motor to said support, a prime mover, a pump actuated by the prime mover for supplying pressure to the motor, a reverse valve interposed between the pump and motor, said reverse valve having a neutral position and a power transmitting position on each side thereof, said valve having a plunger projecting therefrom, a reverse lever pivotally mounted on the saddle, a cycle selector drum coupling the reverse lever to the valve plunger, said drum being rotatable to a plurality of positions to effect a plurality of different cycles of operation of the table and means to adjust the drum from a plurality of operating positions at 40
10. In a machine tool having a translatable support, a power transmission for effecting movement of said support in various cycles including an hydraulic motor, means coupling the motor to 45

- to said support, a prime mover, a pump actuated by the prime mover for supplying pressure to the motor, a reverse valve interposed between the pump and motor, said reverse valve having a neutral position and a power transmitting position on each side thereof, said valve having a plunger projecting therefrom, a reverse lever pivotally mounted adjacent the support, a cycle selector drum coupling the reverse lever to the valve plunger, said drum being rotatable to a plurality of positions to effect a plurality of different cycles of operation of the support, means to adjust the drum from either the front or rear of the machine, means associated with the drum to indicate the particular cycle corresponding to the position in which it is set, and detent means for maintaining the drum in any selected position.
11. In a machine tool having a saddle and a translatable support mounted thereon, a power transmission for effecting movement of said support in various cycles including an hydraulic motor, means coupling the motor to said support, a prime mover, a pump actuated by the prime mover for supplying pressure to the motor, a reverse valve interposed between the pump and motor, said reverse valve having a neutral position and a power transmitting position on each side thereof, said valve having a plunger projecting therefrom, a reverse lever pivotally mounted on the saddle, a cycle selector drum coupling the reverse lever to the valve plunger, said drum being rotatable to a plurality of positions to effect a plurality of different cycles of operation of the support, means to adjust the drum from a plurality of positions at the machine, said drum being mounted on a rotatable shaft extending parallel with the support and slidably mounted on the saddle, the ends of said shaft projecting beyond the sides of the saddle, indicator means on either end of the shaft showing the position to which the drum is set and manual means on each end of the shaft for rotating the drum to a new position.
12. In a machine tool having a saddle and a translatable support mounted thereon, a power transmission for effecting movement of said support in various cycles including an hydraulic motor, means coupling the motor to said support, a prime mover, a pump actuated by the prime mover for supplying pressure to the motor, a reverse valve interposed between the pump and motor, said reverse valve having a neutral position and a power transmitting position on each side thereof, said valve having a plunger projecting therefrom, a reverse lever pivotally mounted on the saddle, a cycle selector drum coupling the reverse lever to the valve plunger, said drum being rotatable to a plurality of positions to effect a plurality of different cycles of operation of the support, means to adjust the drum from a plurality of operating stations at the machine, said drum being mounted on a rotatable shaft extending parallel with the support and slidably mounted on the saddle, the ends of said shaft projecting beyond the sides of the saddle, indicator means on either end of the shaft showing the position to which the drum is set, manual means on each end of the shaft for rotating the drum to a new position, crank means engaging each end of the shaft, and manual control means operatively connected with each of said crank means for effecting reciprocation of the shaft and thereby direct operation of the reversing valve to control the movement of the support.
13. A transmission and control mechanism for a machine tool having an hydraulically actuated transmission including a reverse valve having a neutral position and a power transmitting position on either side thereof, trip mechanism for shifting said valve including a rotatable drum, a peripheral groove in said drum, an operating pin coupled to the valve and extending into said groove, detent means for positioning said drum in a plurality of positions, notches formed in the side of said groove to permit lost motion between the drum and the valve operating pin, a reverse control lever operatively coupled with the drum, load and fire mechanism associated with said lever and operable when a notch in said groove was in a position to receive said pin to fire the valve from one power transmitting position to the other, but only operable to move the valve to a neutral position when there were no notches in the groove opposite the pin.
14. A machine tool having a bed, a grinding wheel journaled on the bed, a saddle adjustably mounted on the bed for movement toward and from the grinding wheel, a table reciprocably mounted on the saddle for movement transversely of the grinding wheel, hydraulic means for effecting reciprocation of the table including a rotatable hydraulic motor, means to effect transverse adjustment of the saddle including a rotatable member, duplicate hydraulically actuated mechanisms for alternately effecting rotation of said member each of said hydraulically actuated mechanisms being coupled in parallel relationship with said hydraulic motor whereby upon reversal of flow to the motor, each of said mechanisms will be actuated but only one will be effective to feed the table laterally of the grinding wheel.
15. A machine tool having a bed, a grinding wheel journaled on the bed, a saddle adjustably mounted on the bed for movement toward and from the grinding wheel, a table mounted on the saddle for reciprocation laterally of the grinding wheel axis, hydraulic means for reciprocating the table including a rotatable hydraulic motor, a pump for supplying pressure to the motor, parallel lines extending to the motor, means to alternately couple each line with pressure to thereby change the direction of rotation of the motor and thereby reciprocation of the table, saddle feeding mechanism including a feed screw, a pair of trigger gears, rack and pinion means for rotating said gears, said racks being reciprocably mounted in cylinders, means to couple one end of each cylinder with one of said parallel lines, means to couple the other end of said cylinder with the other of said parallel lines, means coupling the trigger gears with said lead screw whereby upon simultaneous reciprocation of said rack bars one of said trigger gears will effect rotation of the lead screw whereby the table will be moved laterally at the end of each stroke, and means to vary the extent of movement of each rack bar whereby the feeding movement of the saddle at one reverse of the table may be varied with respect to the feeding movement at the other reversal of the table.
16. A machine tool having a bed, a grinding wheel journaled on the bed, a saddle adjustably mounted on the bed for movement toward and from the grinding wheel, a table mounted on the saddle for reciprocation laterally of the grinding wheel axis, hydraulic means for reciprocating the table including a rotatable hydraulic motor, a pump for supplying pressure to the motor, parallel lines extending to the motor, means to alter-

- nately couple each line with pressure to thereby change the direction of rotation of the motor and thereby reciprocation of the table, saddle feeding mechanism including a feed screw, a 5 pair of trigger gears, rack and pinion means for rotating said gears, said racks being reciprocably mounted in cylinders, means to couple one end of each cylinder with one of said parallel lines, means to couple the other end of said cylinder 10 with the other of said parallel lines, means coupling the trigger gears with said lead screw whereby upon simultaneous reciprocation of said rack bars one of said trigger gears will effect rotation of the lead screw and upon simultaneous movement in the opposite direction the other of said 15 trigger gears will effect rotation of the lead screw whereby the table will be moved laterally at the end of each stroke, and means to simultaneously change the ratchets of said trigger gears whereby 20 each will effect in alternate succession a feeding movement of the saddle in a reverse direction.
17. In a machine tool having a tool spindle and a translatable support movable transversely of the spindle, the combination of a power transmission for moving the support in various cycles 25 including a rotary hydraulic motor, means coupling the motor to said support, a prime mover, a pump actuated by the prime mover for supplying fluid pressure to the motor, a reverse valve 30 interposed between the pump and motor, said reverse valve having a neutral position in which all flow to the motor is terminated, and a power transmitting position on each side thereof for determining the direction of flow to the motor 35 and thereby the direction of movement of the support, a trip controlled member for shifting the valve from either power transmitting position to a neutral position, or the other power transmitting position, adjustable means for selectively connecting the valve positively to said 40 trip controlled member when it is desired to shift the valve to a neutral position after movement of the support in a given direction, or impossibly connect the valve to said member when it is 45 desired to effect a reversal in the direction of movement of the table after movement in a given direction.
18. In a machine tool having a bed, a rotatable tool spindle carried by the bed, a saddle and a 50 table reciprocably mounted on the saddle, the combination of a power transmission for effecting movement of the table transversely of the spindle in various cycles including a rotatable hydraulic motor, transmission mechanism coupling the motor to the table, a prime mover, a pump actuated by the prime mover for supplying fluid under pressure to the motor, a reverse valve 55 interposed between the pump and motor said reverse valve having an axially shiftable plunger movable to a central position for terminating all flow to the motor and thereby stopping the table; to a position on each side thereof for effecting rotation of the motor in opposite directions and thereby different directions of 60 movement of the work support, a shifter mounted parallel to the valve for shifting the plunger thereof, a trip lever pivotally mounted on the saddle adjacent the table, a trip dog carried by the table for automatically actuating said lever, 65 said lever being positively connected to said shifter, and adjustable means for positively connecting the shifter to said valve plunger for movement thereof to a neutral position upon dog actuation of the lever or for impossibly connecting the shifter to the plunger to cause move- 70
- ment of the valve to the opposite power transmitting position to effect an automatic reversal in the direction of movement of the table upon dog actuation of said plunger.
19. In a machine tool having a saddle and a translatable support mounted thereon, the combination of a power transmission for effecting movement of said support in various cycles including an hydraulic motor, means coupling the motor to said support, a prime mover, a pump actuated by the prime mover for delivering fluid under pressure to the motor, a reverse valve interposed between the pump and motor, said reverse valve having a neutral position and a power transmitting position on each side thereof, a trip 80 actuated control lever for said valve pivotally mounted on the saddle, a cycle selector drum coupling the lever to said valve, said drum being rotatable to a plurality of positions to effect a plurality of different connections with the valve including a pin and groove connection, depressions formed in the sides of the groove for providing lost motion between the parts, means to rotate the drum to a first position to provide lost motion between one side of the pin and the 85 groove to effect reversal of the table after movement in one direction; to a second position to provide lost motion on the opposite side of the pin with respect to the groove to effect reversal of the table after movement in an opposite direction; to a third position to provide lost motion on both sides of the pin with respect to the groove to effect reversal of the table at the end of each stroke thereof, and a fourth position providing no lost motion between the pin and groove whereby 90 the table will stop at the end of each stroke thereof.
20. In a machine tool having a saddle and a translatable support mounted thereon, the combination of a power transmission for effecting movement of said support in various cycles including an hydraulic motor, means coupling the motor to said support, a prime mover, a pump actuated by the prime mover for delivering fluid under pressure to the motor, a reverse valve interposed between the pump and motor, said reverse valve having a neutral position and a power transmitting position on each side thereof, a trip 100 actuated control lever for said valve pivotally mounted on the saddle, a cycle selector drum coupling the lever to said valve, said drum being rotatable to a plurality of positions to effect a plurality of different connections with the valve including a pin and groove connection, depressions formed in the sides of the groove for providing lost motion between the parts, means to rotate the drum to a first position to provide lost motion between one side of the pin and the 105 groove to effect reversal of the table after movement in one direction; to a second position to provide lost motion on the opposite side of the pin with respect to the groove to effect reversal of the table after movement in an opposite direction; to a third position to provide lost motion on both sides of the pin with respect to the groove to effect reversal of the table at the end of each stroke thereof, and a fourth position providing no lost motion between the pin and groove whereby 110 the table will stop at the end of each stroke thereof.
21. In a machine tool having a saddle and a translatable support mounted thereon, the combination of a power transmission for effecting movement of said support in various cycles including an hydraulic motor, means coupling the motor to said support, a prime mover, a pump actuated by the prime mover for delivering fluid under pressure to the motor, a reverse valve interposed between the pump and motor, said reverse valve having a neutral position and a power transmitting position on each side thereof, a trip 115 actuated control lever for said valve pivotally mounted on the saddle, a cycle selector drum coupling the lever to said valve, said drum being rotatable to a plurality of positions to effect a plurality of different connections with the valve including a pin and groove connection, depressions formed in the sides of the groove for providing lost motion between the parts, means to rotate the drum to a first position to provide lost motion between one side of the pin and the 120 groove to effect reversal of the table after movement in one direction; to a second position to provide lost motion on the opposite side of the pin with respect to the groove to effect reversal of the table after movement in an opposite direction; to a third position to provide lost motion on both sides of the pin with respect to the groove to effect reversal of the table at the end of each stroke thereof, and a fourth position providing no lost motion between the pin and groove whereby 125 the table will stop at the end of each stroke thereof.
22. In a machine tool having a saddle and a translatable support mounted thereon, the combination of a power transmission for effecting movement of said support in various cycles including an hydraulic motor, means coupling the motor to said support, a prime mover, a pump actuated by the prime mover for delivering fluid under pressure to the motor, a reverse valve interposed between the pump and motor, said reverse valve having a neutral position and a power transmitting position on each side thereof, a trip 130 actuated control lever for said valve pivotally mounted on the saddle, a cycle selector drum coupling the lever to said valve, said drum being rotatable to a plurality of positions to effect a plurality of different connections with the valve including a pin and groove connection, depressions formed in the sides of the groove for providing lost motion between the parts, means to rotate the drum to a first position to provide lost motion between one side of the pin and the 135 groove to effect reversal of the table after movement in one direction; to a second position to provide lost motion on the opposite side of the pin with respect to the groove to effect reversal of the table after movement in an opposite direction; to a third position to provide lost motion on both sides of the pin with respect to the groove to effect reversal of the table at the end of each stroke thereof, and a fourth position providing no lost motion between the pin and groove whereby 140 the table will stop at the end of each stroke thereof.
23. In a machine tool having a saddle and a translatable support mounted thereon, the combination of a power transmission for effecting movement of said support in various cycles including an hydraulic motor, means coupling the motor to said support, a prime mover, a pump actuated by the prime mover for delivering fluid under pressure to the motor, a reverse valve interposed between the pump and motor, said reverse valve having a neutral position and a power transmitting position on each side thereof, a trip 145 actuated control lever for said valve pivotally mounted on the saddle, a cycle selector drum coupling the lever to said valve, said drum being rotatable to a plurality of positions to effect a plurality of different connections with the valve including a pin and groove connection, depressions formed in the sides of the groove for providing lost motion between the parts, means to rotate the drum to a first position to provide lost motion between one side of the pin and the 150 groove to effect reversal of the table after movement in one direction; to a second position to provide lost motion on the opposite side of the pin with respect to the groove to effect reversal of the table after movement in an opposite direction; to a third position to provide lost motion on both sides of the pin with respect to the groove to effect reversal of the table at the end of each stroke thereof, and a fourth position providing no lost motion between the pin and groove whereby the table will stop at the end of each stroke thereof.

movement of said support in various cycles including an hydraulic motor, means coupling the motor to said support, a prime mover, a pump actuated by the prime mover for delivering fluid under pressure to the motor, a reverse valve interposed between the pump and motor, said reverse valve having a neutral position and a power transmitting position on each side thereof, a trip actuated control lever for said valve pivotally mounted on the saddle, a cycle selector drum coupling the lever to said valve, said drum being rotatable to a plurality of positions to effect a plurality of different connections with the valve including a pin and groove connection, depressions formed in the sides of the groove for providing lost motion between the parts, means to rotate the drum to a first position to provide lost motion between one side of the pin and the groove to effect reversal of the table after movement in one direction; to a second position to provide lost motion on the opposite side of the pin with respect to the groove to effect reversal of the table after movement in an opposite direction; to a third position to provide lost motion on both sides of the pin with respect to the groove to effect reversal of the table at the end of each stroke thereof, a fourth position providing no lost motion between the pin and groove whereby the table will stop at the end of each stroke thereof, manual means for actuating said table, a clutch for selectively connecting the manual operating means or the motor to said table, and means for locking said lever in a fixed position during manual operation of the table whereby the same will act as a fixed stop for limiting the movement in either direction of the table.
